UNITED STATES PATENT OFFICE.

PETER SCHEIB, OF DENVER, COLORADO, ASSIGNOR TO THE DENVER ROCK DRILL MANUFACTURING COMPANY, OF DENVER, COLORADO, A CORPORATION OF DELAWARE.

DRILL-SHARPENING MECHANISM.

1,349,169.

Specification of Letters Patent. Patented Aug. 10, 1920.

Application filed March 25, 1918. Serial No. 224,616.

To all whom it may concern:

Be it known that I, PETER SCHEIB, a citizen of the United States, residing at Denver, in the county of Denver and State of Colorado, have invented certain new and useful Improvements in Drill-Sharpening Mechanism, of which the following is a specification.

The present invention relates to means for sharpening drills, and is more particularly intended for the proper sharpening of so-called "hand steel," namely that which is held in the hand of the operator and struck by a manually operated hammer.

One of the principal objects is to provide mechanism that will effectively sharpen this steel and insure its proper shaping.

Another object is to provide mechanism of the above character which may be utilized on a well known type of mechanically operated drill sharpening apparatus.

The preferred embodiment of the invention is illustrated in the accompanying drawings, wherein:—

Figure 1 is a plan view of a portion of one of the die members of a well known type of drill sharpener, showing the improvements in place thereon.

Figs. 2 and 3 are respectively sectional views on the lines 2—2 and 3—3 of Fig. 1, but including the upper die members.

Fig. 4 is a sectional view at right angles to Figs. 2 and 3.

Fig. 5 is a detail view of a drill bit at one stage of construction.

Fig. 6 is a similar view of the completed bit.

Similar reference numerals designate corresponding parts in all the figures of the drawings.

In the embodiment illustrated, the usual die members 7 and 8 are provided that are relatively movable toward and from each other. Each member is provided with a socket 9 to receive the ordinary shaping dies 10, with which co-operates a dolly 11 in a manner well understood to those skilled in the art.

In the present embodiment the members 7 and 8 are provided alongside the sockets 9 with recessed seats 12 in which are detachably located die blocks 13. These blocks

are provided in their opposing faces with sockets 14, a part of each socket being semi-circular in cross section, as illustrated in Fig. 3, and the remainder being angular in cross section, as illustrated in Fig. 2. In the angular portions are detachably located cutting dies 15. Each of these dies is square in cross section, thereby producing four cutting edges, one of which projects from the socket and co-operates with the corresponding projecting edge of the other die, as will be clear by reference to Fig. 2. The angle formed by the projecting faces of these cutting dies corresponds to the desired angle of the cutting bit. In the semi-circular portions of the sockets 14 are detachably fitted cylindrical dies 16 that also project from the faces of the die blocks, as will be clear by reference to Fig. 3. The curved faces of these dies are preferably roughened or knurled as illustrated in Fig. 1. They are held against rotation by keys 17 detachably fitted in registering seats 18 formed in the die blocks and the dies. Preferably each of the dies 16 has a plurality of the seats, so that the keys 17 can be detached and the dies turned to present different portions of the surfaces for operative work, as herein-after described. It will also be noted that the circular dies have bores 19 therethrough and that when the parts are in place, as illustrated in Fig. 4, the dies are held against detachment from the open ends of the sockets 14 by the shaping dies 10. It will be noted that when the die members are together, the dies 16 are spaced apart slightly.

As is well known, the corners are usually worn and rounded off, and effective drilling is dependent to a marked degree upon the securing of these corners and their proper flare. With the present mechanism in sharpening the drill bit, the steel is first heated, and one of the corners is placed between the dies 16 and the die members are brought together upon the same. The corner is then drawn out, after which the other corner is correspondingly operated upon, producing a structure of the general character illustrated in Fig. 5. When this has been completed, the bit is placed between the dies 15 and the die members are again brought together, not only cutting off a square edge,

as will be clear by reference to Fig. 2, but properly shaping the intersecting faces that produce said edge and resulting substantially in the structure illustrated in Fig. 6. 5 It will thus be seen that a bit can be properly shaped and sharpened by one heating and can be produced quickly and expeditiously without the exercise of the care that is necessary in hand sharpening. When the 10 operative edges of the cutting dies become dull or misshapen from any cause, it is only necessary to remove them, partially rotate them and reinsert them, whereupon new cutting edges are presented. This re- 15 moval can be accomplished by removing the die blocks from their seats, and inserting a suitable ejecting tool through the bores 19 of the dies 16. When the coöperating faces of said dies 16 become worn new 20 portions thereof can be presented by removing the keys 18 and partially rotating the dies, or turning them end for end.

From the foregoing, it is thought that the construction, operation and many advantages of the herein described invention will be apparent to those skilled in the art, without further description, and it will be understood that various changes in the size, shape, proportion, and minor details of construction, within the scope of the claims 25 may be resorted to without departing from the spirit or sacrificing any of the advantages of the invention.

Having thus fully described my invention, what I claim as new, and desire to secure by Letters Patent, is:—

1. In drill sharpening apparatus, the combination with relatively movable die members, said members having an open 40 drill steel receiving mouth between them, of dies carried by the die members and located transversely to the die receiving mouth, said dies having coacting rounded corner drawing faces.

45 2. In drill sharpening apparatus, the combination with die members relatively movable toward and from each other and having a drill steel receiving mouth between them, of dies carried thereby and extending transversely to the die-receiving mouth, said dies having curved operative faces, and means for securing the dies with different portions of the faces in coacting relation.

50 3. In drill sharpening apparatus, the combination with die members relatively movable toward and from each other and having die receiving sockets, and dies mounted in the sockets, said dies being rotatable to present different active faces, 55 seats formed in the dies and members and registering when the former are differently placed in the sockets, and keys engaging in the seats for securing the dies in place.

60 4. In drill sharpening apparatus, the combination with die members relatively 65

movable toward and from each other and having sockets, of dies angular in cross section forming a plurality of cutting edges, said dies being engaged in the sockets and being detachable to permit the use of any 70 of the cutting edges, the angular faces of the dies corresponding to the desired angular bit faces to be cut.

5. In drill sharpening apparatus, the combination with die members relatively 75 movable toward and from each other and having angular overhung sockets opening through their adjacent sides, of dies in the sockets and correspondingly angular in cross section, forming a plurality of cutting 80 edges, said dies having certain of said edges projecting from the sockets and being detachable to permit the use of any of the cutting edges, the angular faces of the dies corresponding to the desired angular bit faces 85 to be cut.

6. In drill sharpening apparatus, the combination with die blocks relatively movable toward and from each other and having sockets partly angular and partly 90 curved in cross section, of drawing and cutting dies located end to end in the sockets and each held against longitudinal displacement by the other.

7. In drill sharpening apparatus, the 95 combination with die blocks relatively movable toward and from each other and having sockets partly angular and partly curved in cross section, of drawing and cutting dies detachably located end to end in 100 the sockets, certain of the dies having openings therethrough to receive an ejector for the other of said dies.

8. In drill sharpening apparatus, the combination with die members having recessed seats, of die blocks in the seats having sockets in their opposing faces, and dies detachably engaged in the sockets.

9. In drill sharpening apparatus, the combination with die members having recessed overhung seats, said seats having open ends, of die blocks in the seats having sockets in their opposing faces, and dies engaged in the sockets and detachable through the open ends thereof and other dies carried by 115 the members and constituting retaining means for the first mentioned dies.

10. In drill sharpening apparatus, the combination with die blocks having recessed seats provided with open ends, of coacting 120 dies in the seats, and shaping dies movable with the die blocks and constituting retaining means for the said coacting dies.

11. In drill sharpening apparatus, the combination with die members relatively 125 movable toward and from each other, said die members having recesses formed side by side in their opposing faces, die blocks located in certain of the recesses and having open ended sockets, dies in the sockets, and 130

shaping dies in the other recesses of the die members, said latter dies constituting retaining means for the first mentioned dies.

12. In drill sharpening apparatus, the combination with die blocks relatively movable toward and from each other, of sets of drill bit drawing and cutting dies carried by the blocks, the drawing dies being dis-

posed in spaced relation when the cutting dies are together.

In testimony whereof I affix my signature in the presence of two witnesses.

PETER SCHEIB.
